UNITED STATES PATENT OFFICE.

CLARENCE C. SHIPP, OF INDIANAPOLIS, INDIANA.

HOUSING CONSTRUCTION FOR STEAM RADIATORS.

Application filed September 15, 1924. Serial No. 737,723.

To all whom it may concern:

Be it known that I, CLARENCE C. SHIPP, a citizen of the United States, residing at Indianapolis, in the county of Marion and State of Indiana, have invented a new and useful Improvement in Housing Construction for Steam Radiators, of which the following is a specification.

This invention relates to improvements in sheet metal housings for steam radiators, and the object is to provide such a housing in two longitudinally and vertically divided parts, for convenient assembly and dismemberment, which will not buckle and spring open to leak at the joints.

Another object is to provide a strong and durable housing in jointed sections such that the joints cannot be easily tampered with and loosened, and the object is to improve the construction in such other ways as will hereinafter appear and the novel features thereof specified in the claims.

In the accompanying drawing—

Fig. 1, is a perspective view of my invention assembled in operative position. Fig. 2, is a top plan view of a radiator housing detached from the radiator and from associated parts of the housing, one end being shown in horizontal section and the other end with the top clamp strip removed. Fig. 3, is an elevation and partial section of the upper portion of one end of the housing on a larger scale than in the preceding views. Fig. 4, is an inside view of a fragment of a top roll. Fig. 5, is a perspective view of my preferred form of joint connecting the front and rear housing members, and Fig. 6, is a like view of a modified joint structure.

Like characters of reference indicate like parts in the several views of the drawing.

The radiator is formed of any desired number of similar sections 7, as shown in Fig. 1, in which illustration the near end-section is omitted to expose that end of the housing.

The housing is made of sheet-metal, in two principal and separable parts, comprising a front wall 8, having integral half-ends 9, 9, and a rear wall 10, having integral half-ends 11, 11. The adjacent half-ends of each front and rear wall are inserted between the end section and the next adjacent section of the radiator, and their vertical edges are united by a slip-joint. One of the half-ends, here shown as the rear

one has its vertical edge portion 12 bent back upon itself and then bent oppositely to form the holding member 13, between which and the portion 12, the vertical edge 60 of the front half-end 9, is slidably inserted, in the manner shown, and the edges are held securely against buckling open and leaking air at the joints. The half-ends thus joined are drawn together and held by bolts 14, 65 which pass through the front and back walls. The top edges of the joined half-ends are held and reenforced by a clamp-bar comprising a sheet metal channel bar 15, which is slipped over them. This bar 70 also acts as a spacer between the walls 8 and 10.

The top edges of the walls 8 and 10 are finished and reenforced by a sheet metal roll having a depending flange 16 which 75 contacts the inner side of said respective walls. Stove-bolts 17, pass through the flanges 16 and adjacent walls to retain the rolls in their places.

The ends of the flanges 16, have slots 18 80 (see Fig. 4), to avoid the bolts 14, in the assembly of the parts. The nuts and heads of the bolts are covered by the rolls, and the clamp-bars 15, have end lugs 19 (see Fig. 3), which project under the flanges to lock 85 the bars 15 against removal.

A box-base 21, attached to the wall and communicating with a wall-box (not shown) admitting outside air, has an up-turned end which telescopes in the lower end of the 90 radiator housing. The telescoped end has slots to receive stove-bolts 22, by which the wall-box and housing are united.

In the modification shown in Fig. 6, the channel at the joint is formed by a separate 95 strip 20, suitably bent, and riveted to the rear half-end 11.

I claim—

1. A radiator housing of sheet metal in a plurality of separable parts joined together at the ends of the housing by a slip-joint one side of which is channeled, channeled clamp-bars on each of said jointed ends having the housing ends inserted in the channels, and tie-rods holding the housing 100 front and back against the ends of the clamp-bars and stiffening rolls on the edges of the housing, front and back, enveloping the tie-rod terminals.

2. A radiator housing of sheet metal in a 110 plurality of separable parts joined together at the ends of the housing by a slip-joint

one side of which is channeled, channeled clamp-bars on each of said jointed ends having the housing ends inserted in the channels, tie-rods holding the housing front and back against the ends of the clamp-bars, stiffening rolls on the edges of the housing front and back having inside de-

pending flanges, and end lugs on the clamp-bars engaging the flanges of the rolls to lock the clamp-bars.

Signed at Indianapolis, county of Marion, State of Indiana, this the 9th day of Sept. 1924.

CLARENCE C. SHIPP.
